Fig. 11

Fig. 8

Fig. 10

Fig. 9

Fig. 1

FIG. 1 is a perspective view of an electronic calculating machine showing my new design;

FIG. 2 is a plan view thereof;

FIG. 3 is a right side elevational view thereof;

FIG. 4 is a left side elevational view thereof;

FIG. 5 is a front elevational view thereof;

FIG. 6 is a bottom view thereof;

FIG. 7 is a cross sectional view taken on line 7—7 of FIG. 5;

FIG. 8 is a plan view thereof showing the machine in its closed position;

FIG. 9 is a right side elevational view of FIG. 8;

FIG. 10 is a left side elevational view of FIG. 8;

FIG. 11 is a front elevational view of FIG. 8;

FIG. 12 is a rear elevational view thereof; and

FIG. 13 is a bottom view of FIG. 8.

I claim:

The ornamental design for an electronic calculating machine, as shown.
